UNITED STATES PATENT OFFICE.

WALTER M. INGRAM, OF BALTIMORE, MARYLAND.

MARKING-MACHINE.

1,331,924.

Specification of Letters Patent. Patented Feb. 24, 1920.

Application filed May 17, 1919. Serial No. 297,820.

To all whom it may concern:

Be it known that I, WALTER M. INGRAM, a citizen of the United States of America, residing in the city of Baltimore, State of Maryland, have invented certain new and useful Improvements in Marking-Machines, of which the following is a specification.

The present invention relates to a stamping machine particularly adapted for use 10 in the marking of checks, the object of the invention being to produce a simplified apparatus of increased utility which can be manufactured conveniently in large numbers at a minimum outlay.

15 Described in general terms the machine consists of a type carrying or printing member, a guide for the same which may be a track or way, an inking member or pad with a cooperating guide which may also be a track or way intersecting the line or plane of the first-named guide, and two connecting rods which in a general way are oppositely disposed and togglewise related or 20 pivotally connected and actuated from said 25 pivotal connection or toggle joint by moving the pivot or joint on a predetermined path, imparting to the printing member an alternate short and long stroke. The pad is reciprocated on its intersecting path and intercepts 30 the printing member and inks the type at the end of the short stroke of the latter and moves out of the path of the printing member to provide for the printing or long stroke of the printing member.

35 More particularly, this is accomplished by moving said pivot or joint through and by the dead point of the connecting rod which actuates the printing member by a short arc or distance on one side, *i. e.*, when 40 the pad is advanced into the path of the printing member, on the short stroke; and by a comparatively long arc or distance on the other side when the pad is withdrawn and the printing member descends for the 45 long or printing stroke.

50 Preferably the guide which controls the motion of the inking member, while it intersects the path of the printing member substantially at right angles, is inclined in the direction from which the printing member approaches it, and while the pad itself is supported at right angles to the direction of motion of the printing member, the two members approach each other on the inking 55 stroke at an angle of more than 90°.

Preferably the machine is gearless, at least as to the principal or essential motions.

Figure 1 is a front elevation, *i. e.*, looking from the position of the operator.

Fig. 2 is a side elevation looking from the right, the apparatus being shown in both these instances in inking position.

Fig. 3 is a section on line 3, 3 of Fig. 1 showing the machine in printing position.

Figs. 4 and 5 are detailed views of the 65 printing member.

Fig. 6 is a detail of the crosshead pin and the mountings therefor on the printing member.

Referring to the drawings by numerals, 70 the machine includes two upright side frames 1 which may be of stamped or pressed material secured to a suitable base 2 in parallel relation, a vertically reciprocating printing member 3 sliding in ways 4 on the side frames, an inking member 5 mounted to slide transversely to the path of the printing member in ways 6 on the frames 1; an oscillating crank shaft 7 on which are pivoted at a suitable radius oppositely disposed connecting rods 8, 9 which actuate the printing and inking member 3, 5, respectively, being connected thereto by crosshead pins 10, 11.

More particularly it will be noted that 85 the crank arm 12, the connecting rod 8, the printing member 3, the ways 4, the connecting rod 9, the crosshead pin 11 and ways 6 are so related that the crank being stopped in its extreme positions by the relation of the parts, which limiting positions are determined by the contact of the type 13 with the plate 14 at one end of the stroke and contact of the type with the inking pad 5 in inking position, or of the connecting 90 rod 9 with the shaft. The crank moves alternately through arcs of different lengths on each side of the dead center of the connecting rod 8, or the adjacent ends of the togglewise arranged connecting rods are 95 moved on a fixed path which carries them through the dead point of the printing member and its connecting rod and by unequal distances on each side of said point, causing the printing member 3 to execute, 100 first, a long stroke and then a short stroke while the inking member whose connecting rod always remains on one side of its dead center or substantially so, makes a single 105 long stroke, moving into the path of the 110

printing member and engaging the latter at the end of the latter's short stroke and moving out of the path of the printing member to permit the latter to pass it on the printing stroke.

Referring to the details of the structure, the printing member 3 consists of a frame 15 which may be most conveniently cut or stamped from a single flat piece of sheet metal, the same being flanged or turned at right angles at the bottom edge at 16 and preferably being supplied with an edge facing 17 of paper, fiber or leather to engage the ways, giving a noiseless operation. To the bottom flange 16 is secured a type-carrying member 18 shown in detail in its preferred form at 49 in Figs. 4 and 5. This plate or type carrier has its edges folded over as indicated at 19 to receive the type plate 20 and has a fastening device for the latter. There is a transverse spring plate or band 21 extending transversely of the type carrier on top, spaced up therefrom, the same serving as a holder for a ball 22 which engages a socket 23 in the band 21 and an opening 24 in the carrier plate, so that a section of the ball extends through the carrier plate engaging a corresponding indentation or hole 25 in the type plate. It will be apparent that the ball is mounted to yield so that the type plate while held frictionally, can be withdrawn when sufficient pressure is applied. The mounting of the crosshead pin is illustrated in detail in Fig. 6, the same consisting of a band or strip 26 bent in the form of a shallow or short U, the base of the U being secured transversely to the top of the frame or plate 15. The ends of the arms of the U are bored or apertured at 27 to form journal bearings for the pin 10. The latter is held in position by means of a collar 28 secured to the pin a short distance from one end, a collar 29 secured to the pin near the center to position the connecting rod, a spring 30 bearing at one end against the connecting rod, pressing it against the collar 29 and at the other end against the end of the U-shaped bracket 27 opposite to the collar 28.

To set up the crosshead pin, the end at 31 is passed through the corresponding opening in the bracket 26, the spring 30 bearing against the bracket and the connecting rod, is compressed until the opposite end of the pin may be inserted in the aperture at the opposite end of the U. When this is done and the parts released, the spring brings the collar 28 into a bearing against the U. The ways 4 on the frame most conveniently consist of a channel-bar stamped out of thin sheet metal and riveted or screw-fastened to the frame.

The ways 6 for the inking pad are similarly constructed and preferably placed at

an angle to the ways 4 of a little more than 90°, so that as the inking member and printing member come in contact, they approach at an angle of more than 90°, so that there is a certain amount of direct impact rather than a tendency of one member to slide by the other, at the same time the pad 36 which is carried by the inking member 5 is kept at right angles to the printing member.

In other words, the inking member consists of a carriage 37 of U-shaped cross-section having top outwardly turned flanges 38 at an angle to the bottom or cross-member 39 of the U which carries the pad, the angle being preferably equal to the deflection of the angle between the ways from the right angle. These flanges are preferably faced as the edges 17 of the printing member. The crosshead pin 11 is also similarly mounted to the crosshead pin 10 by means of a spring 39 and collars 40 corresponding to the two collars on the crosshead pin 10. The pad 36 is secured to a free plate 41 preferably by the overturned edges 42 of plate 41, see Fig. 1, and this plate 41 has a tongue 43 bent backward over the body of the plate as indicated in Fig. 3, the same having a resilient property and carrying a pin 44 which engages a suitable socket 45 in the bottom of the carriage 37 when the plate 41 carrying the pad 36 is in position, that is, the bottom or cross-arm of the U-shaped member forming the carriage, is pressed between the tongue 43 and the body of the plate 41, the pin engaging the socket 45 in the said cross-arm.

While the shaft which actuates the reciprocating printing member and inking member may be provided with separate cranks 105 for actuating the connecting rods 8 and 9 in the present instance, there is a single crank 12 and a single crank pin 12' which engages both the connecting rods 8 and 9.

In operation, the machine, which may be 110 electrically or mechanically actuated, is driven by oscillation of the shaft 7 by any suitable means moving the crank pin 12' alternately through two arcs or paths of different lengths on opposite sides of the dead 115 point of the connecting rod 8 which actuates the printing member so that the reciprocating printing member performs alternately a long and a short stroke. The long stroke brings it in contact with the 120 plate 14 which is stationary in its path and the short stroke brings it in contact with the inking pad 36 or inking member 5. The latter is moved by a single stroke into and out of the path of the printing member at 125 the end of the short stroke of the latter, in other words, the pin 12' which may be actuated in any suitable manner and the function of which is to carry the adjacent ends of the connecting rods on a fixed path, 130

moves the swinging end of the connecting rod 9 on a single arc or path mainly on one side of its dead center through which it preferably does not pass or passes to only a slight extent.

The improvement resides in the simplicity of the structure, ease of operation, absence of gears, and the ease, cheapness and convenience with which it may be produced in large quantities.

I have thus described a machine embodying my invention in its preferred form in order that its nature and operation may be clearly understood. However, the specific terms herein are used descriptively rather than in their limiting sense, the scope of the invention being defined in the claims:

What I claim and desire to secure by Letters Patent is:

1. In a printing or marking machine, in combination a printing member, guiding means therefor, confining it to a predetermined path, an inking member, guiding means therefor, confining it to a fixed path, oppositely disposed, togglewise related connecting rods, one actuating each said member, means for moving the adjacent ends of the connecting rods on a fixed path through and by the dead center of the connecting rod which actuates the printing member, giving the latter an alternate long and short stroke, moving the inking member into the path of the printing member at the end of the short stroke, and removing it from the path of the printing member during the long stroke.

2. In a printing and marking machine, in combination a reciprocating printing member, guiding means for the same, a reciprocating inking member and a guide therefor, the path of the two members being thus closed to intersect an oscillating crank shaft parallel to the line of intersection of the

planes of said paths, a connecting rod for each said member actuated from said shaft, the crank being so placed relatively to the path of the printing member that it swings through the dead point of said member and moves through unequal arcs on each side of said dead point, giving an alternate long and short stroke of the printing member, the inking member being moved by its connecting rod into the path of the printing member during the long stroke of the latter and out of the path of the printing member during its short stroke.

3. In a printing or marking machine, in combination a printing member, guiding means for the same, permitting it to move on a fixed path, an inking member, guiding means for the same permitting it to move on a fixed path, the two paths intersecting, a connecting rod for each said member, a shaft actuating said connecting rods, the crank pin radius of the connecting rod which actuates the printing member being so related to the path of the latter that it swings by unequal arcs on each side of the dead center of the connecting rod of the printing member, the connecting rod carrying the inking member being moved substantially on one side only of its dead center so that while the printing member has a long and short stroke, the inking member has a single stroke which moves it into the path of the printing member at the end of the short stroke and out of the path of the printing member at the end of the long stroke.

Signed by me at Baltimore, Maryland, this 17th day of May, 1919.

WALTER M. INGRAM.
